UNITED STATES PATENT OFFICE.

ORRIN B. PECK, OF CHICAGO, ILLINOIS, ASSIGNOR TO MELINDA PECK, OF SAME PLACE.

APPARATUS FOR CENTRIFUGALLY TREATING MOLTEN MATERIAL.

SPECIFICATION forming part of Letters Patent No. 433,144, dated July 29, 1890.

Application filed March 3, 1890. Serial No. 342,435. (No model.)

To all whom it may concern:

Be it known that I, ORRIN B. PECK, a citizen of the United States, residing at Chicago, Illinois, have invented a new and useful Improvement in Apparatus for Centrifugally Treating Molten Material, of which the following is a specification.

The object of my invention is to provide a simple and economical means for treating and removing the molten material, and also for removing the gas and steam that may be formed; and the invention consists in the features and combinations hereinafter described and claimed.

15 In the drawings, Figure 1 is a vertical elevation, partly in section, of the centrifugal machine, together with the apparatus for removing the material and the gas and steam; Fig. 2, a plan view of the entire apparatus; 20 Fig. 3, a horizontal section on line 3 of Fig. 1, looking in the direction of the arrows; and Figs. 4, 5, and 6, vertical sections illustrating modified forms of discharging-spouts. The last four figures are on an enlarged scale. 25 Fig. 7 is a detail plan view of a screen.

V is the receiving-vessel; A, the curb surrounding the same; B, the shaft for supporting and revolving the vessel; C C, journal-bearings for supporting and maintaining the 30 vertical position of the shaft; D, the discharge pipe or passage; E, a centrifugal pump; F, a discharge-pipe leading off from the pump; G G, rollers or crushers mounted in the discharge-pipe and driven by means of a belt-wheel G' and cog-wheels g g'; g', a weighted lever intended to hold the rollers G G in proper relative position to each other; II, an exhaust or suction fan connected with the discharge-passage D by means of pipe h, and 35 provided with a discharge-pipe II'; I, a suitable engine for supplying power to drive the pump and fan; J, an engine for supplying power to drive the centrifugal machine; J', the driving-wheel thereof, and K the driving-belt.

40 The receiving-vessel, curb, shaft B, with its bearings, engine for driving the centrifugal machine, and all parts not hereinafter more particularly set forth have been shown and 45 described in prior patents and applications, and their construction being obvious from

an inspection of the drawings, they require no further description.

From a point, preferably near the bottom of the curb A, I lead off a suitable discharge 55 pipe or passage D and connect it with a centrifugal or other force-pump E, by means of which the material which flows out of the curb is forced through the pipe F to any place desired. Through imperfect or insufficient 60 cooling, comparatively large lumps of material are liable to be formed in the machine, and, passing down through the discharge-passage, will clog or interfere with the action of the pump. To prevent this interference 65 with the pump, I prefer to provide rollers G G. These rollers are supported, as shown, in the discharge-passage, and are provided with cog-wheels g, which mesh together. The shaft of one of these rollers is provided with a belt-wheel G', driven by any suitable source of 70 power, as the engine I. These rollers are constantly revolving, and should be so placed in the discharge-pipe that the material coming through the machine is forced to pass between 75 them, and any lumps too large to pass between the rollers will be crushed or reduced in size by their revolution. One of these rollers or crushers G is supported in a movable bearing L, the object of this being to allow a slight 80 play to the rollers.

In Fig. 4 I have illustrated a modification of this crushing device, wherein the surfaces of the crushing-rollers are provided with corrugations.

85 In Fig. 6 I have shown a modification wherein I have substituted for the crushing-rollers G a movable crushing-jaw M, operated by a toggle-joint N, or other suitable mechanism. In the modification shown in Fig. 5, 90 D' is the suction-pipe of the pump E, and D is the end of the discharge-spout, preferably somewhat contracted toward its lower end. At some point between the pump E and the curb of the centrifugal machine I provide a 95 screen O, made of such size as to permit only of the passage of such material as is proper to pass through the pump. The larger pieces which are rejected by the screen pass down and out of a suitable opening in the pipe or 100 passage D.

In the use of the centrifugal machine for

the treatment of molten material a large amount of gas and steam is formed, and to provide the means for carrying off such gas and steam I employ a suitable suction-fan H, 5 or other means connected, as shown in the drawings, with the discharge pipe or passage by means of the pipe h. The fan may, however, be connected, directly to the curb of the machine or any other suitable part of the 10 apparatus.

In my applications Serial Nos. 342,425, 342,427, and 342,437, filed at the same time as my application herein, I have set forth the 15 process and some of the features of construction disclosed, but not claimed in this case.

I claim—

1. The combination, with a centrifugal machine for the treatment of molten material, of an exhaust-fan for drawing off steam or 20 smoke, and a pump for pumping away material and water, substantially as described.

2. The combination, with a centrifugal machine for the treatment of molten material, of a force-pump for pumping away the water 25 and material, a spout connecting the machine and pump, and an exhaust-fan communicating with the pump, substantially as described.

3. The combination, with a centrifugal machine for the treatment of molten material, of a force-pump for pumping away the water 30 and material, a spout connecting the machine and pump, and means for crushing coarser material on its passage from the machine to the pump, substantially as described.

4. The combination, with a centrifugal machine for the treatment of molten material, 35 of a force-pump for pumping away the water and material, a spout connecting the machine and pump, an exhaust-fan communicating with the spout, and means for crushing coarser 40 material on its passage from the machine to the pump, substantially as described.

5. The combination, with a centrifugal machine for the treatment of molten material, of a force-pump for pumping away the water and material, a spout connecting the machine and pump, an exhaust-fan communicating with the spout, and rollers in the spout for crushing coarser material, substantially as described.

ORRIN B. PECK.
